L. F. SCHAUBLE

VACUUM OIL BURNER

Filed Sept. 7, 1926

UNITED STATES PATENT OFFICE.

LOUIS F. SCHAUBLE, OF SEATTLE, WASHINGTON.

VACUUM OIL BURNER.

Application filed September 7, 1926. Serial No. 133,825.

The invention is an oil burner, in which the oil is held in one chamber with steam in an adjoining chamber, having a single partition between the two chambers, and a double valve arrangement through which more or less steam may pass thru the burner, and more or less oil drawn thru by the steam, and also a resiliently held piston in a steam cylinder for automatically operating the said valve to maintain a constant steam pressure.

The object of the invention is to provide an automatically operated double regulating valve in an oil burner.

Another object of the invention is to provide means for controlling amounts of oil and steam passing thru an oil burner automatically.

Another object is to provide a double chambered oil burner with direct connected valves from the said chambers.

A further object of the invention is to provide a burner having oil and steam chambers with a partition between them with the steam heating the oil and drawing the oil thru the burner.

And a still further object is to provide an oil burner having adjacent oil and steam chambers with a common valve member arranged to allow the oil to be drawn thru by steam, and the amounts of each governed respectively.

With these ends in view the invention embodies a unitary casing having a chamber for oil, another chamber for steam, a single partition between the two chambers, a double valve member, with variable openings to each of the said chambers, a steam cylinder with the piston directly connected to the valve member, and a spring for resiliently holding the valve member in the open position against the steam pressure of the cylinder.

Other features and advantages of the invention will appear from the following description taken in connection with the drawings, wherein:

Figure 1 is a longitudinal section thru the device.

Figure 2 is a side view showing an alternate design.

In the drawings the device is shown as it would be made wherein numeral 1 indicates the oil chamber, numeral 2 the steam chamber, numeral 3 the valve member, and numeral 4 the operating cylinder.

The chambers 1 and 2 are formed in a unitary casing 5 which may be cylindrical in shape and are arranged with a partition 6 between them so that the oil will be heated by the steam thru the partition. The chamber 1 is provided with an inlet opening 7 and the chamber 2 with a similar opening 8 and the outer side of the casing 1 is provided with a boss 9 into which the burner 10 is received and held by a lock nut 11. At the opposite end of the casing 5 is a hub 12 to which the cylinder 4 is attached and in which the inner end 13 of the valve member 3 is slidably held as shown.

The valve member 3 is formed with a cylindrical shaped portion 14 having an opening 15 in it and small openings 16 at the inner end of the opening 15. A shoulder 17 is provided which seats against a beveled surface in a hub in the partition 6 to form a valve and at the end of the member is another beveled surface 18 that cooperates with a similar beveled surface at the inner end of the burner 10, to form an open valve thru which the oil may be drawn from the chamber 1 by the steam. Beyond the shoulder 17 are other openings 19 which permit a larger amount of steam to pass from the chamber 2 into the opening 15 which will in turn draw a larger amount of oil from the chamber 1 as it passes into the burner.

In the inner end 13 of the valve member 3 is a slotted opening 20 in which a head 21 of a rod 22 may be held as shown. The rod 22 extends into the cylinder 4 and is held in the head 23 as shown. The cylinder which is held to the casing 5 thru a yoke 24 is provided with a steam inlet 25 and the piston 23 is resiliently held toward the head of the cylinder by a spring 26. This provides manual mechanical means for holding the oil and steam valves open and it will be observed that as the steam pressure increases in the cylinder 4 it will move the pistons and partially close the valves, or

move them to the position shown in Figure 1.

In the design shown in Figure 2 the cylinder 4 is replaced by a hand wheel 27 and the rod 22 is threaded in a nut 28 in the outer side of the yoke 24 and it will be observed that by rotating the rod it will be possible to move the valve member backward or forward any appreciable amount to adjust the valve.

10 It is understood that changes may be made in the construction, arrangement or design of any of the parts, or in the general arrangement without departing from the spirit of the invention.

15 The construction will be readily understood from the foregoing description. To use the device it may be assembled and arranged as shown and described, and the steam from the boiler heated by the burner

20 connected to the inlet connections 8 and 25.

It will be noted that the steam will keep the partition 6 heated and thereby heat the oil in the chamber 1 and it will also hold the piston 23 in the position shown with

25 the valves partially closed; however as the steam pressure in the boiler decreases it will permit the spring to open the valves slightly more than shown and thereby admit more steam to the burner which will

30 in turn draw more oil to the burner and thereby build up the fire to generate more steam. As the steam pressure again increases the steam will return the valves to the position shown and thereby automatically con-

35 trol the fire to provide constant pressure.

Having thus fully described the invention, what I claim as new and desire to secure by Letters Patent, is:—

1. In an oil burner of the class described, 40 a cylindrical chamber having an oil inlet opening at one side, another similar chamber in juxtaposition to the said former chamber with a steam inlet opening at one side, both chambers being formed in a common

45 casing with a web between them, an outlet casing having an opening with outwardly inclined sides extending from the center of the oil chamber, a sleeve forming a valve member slideable in a hub in the web be-

50 tween the oil and steam chambers and having an enlarged end slideable in a hub in the outer end of the said steam chamber, said valve member having a beveled sur-

55 face at the end extending into the oil chamber corresponding with a similar beveled surface at the inner end of the outlet casing and a shoulder adjacent the opposite end also having a beveled surface engaging a similar beveled surface at the inner end

60 of the hub of the web, said valve member having a small opening from the steam chamber to a cylindrical opening on the inside thereof and extending from a point slightly behind the said small opening to

65 the opposite end of the said member, said

small opening being positioned behind the said shoulder, said member also having a plurality of small openings extending through the wall thereof and into the said inner cylindrical opening, said openings 70 positioned on the opposite side of the said shoulder and adjacent the said beveled surface thereon, said valve member also having a plurality of oil rings extending around the outer surface in the hub in the web 75 and also at the opposite end of the steam chamber, the enlarged end of the said valve member also having a recessed opening to receive a head on the end of a piston rod, and a suitable resiliently held piston at 80 the opposite end of the said rod positioned in a cylinder connected to the steam chamber hub of the said burner casing and provided with a steam inlet opening.

2. In a burner of the class described, an 85 oil chamber having an intake opening, a steam chamber also having an intake opening and in juxtaposition to the said oil chamber, a common casing inclosing the two said chambers with a web between the 90

said chambers, a burner casing extending from the center of the said oil chamber, a sleeve forming a valve member slidably held in a hub in the web between the said chambers, valve surfaces on the said valve 95 member adaptable to engage similar surfaces at the end of the hub of the web that extends into the steam chamber, similar valve surfaces at the end of the said valve member corresponding with similar sur-

faces at the inner end of the said burner casing and held a slight distance from the inner end of the said burner casing by the valve surfaces in the steam chamber, said 100

valve member having a cylindrical opening therein extending from the end adjacent the said burner casing to a point about midway of the said steam chamber, said valve member having a small opening be-

105 hind the valve in the steam chamber and extending into the said cylindrical opening and also a plurality of openings on the op-

posite side of the said valve and extending into the said cylindrical opening, and suit- 110 able means for adjusting the position of the said valve member to regulate the amounts of oil and steam passing through the said burner.

3. In an oil burner of the class described, 115 an oil chamber having an inlet opening, a steam chamber also having an inlet opening said chambers positioned in a common cas- 120 ing with a web between them, said oil cham- 125 ber having an outlet opening in the center of the outer side thereof, a cylindrical valve member slideable in a hub in the web be-

tween the two said chambers and having a valve member at the end thereof to regu- 125 late the outlet opening of the said oil cham- 130 ber, another valve formed in the said steam

chamber by the said valve member to partially regulate the flow of steam from the said steam chamber to the said outlet opening of the said oil chamber through an

5 opening in the center of the said valve member, said valve member also having a small opening from the cylindrical opening on the

inside thereof to the steam chamber which is not affected by the said valve, and means for adjusting the position of the said valve member.

In testimony whereof I affix my signature.

LOUIS F. SCHAUBLE.
